UNITED STATES PATENT OFFICE.

SAMUEL K. JENSIK, OF PUEBLO, COLORADO.

CALENDAR.

1,048,413.

Specification of Letters Patent. Patented Dec. 24, 1912.

Application filed June 29, 1912. Serial No. 706,627.

To all whom it may concern:

Be it known that I, SAMUEL K. JENSIK, a citizen of the United States, residing at Pueblo, in the county of Pueblo and State 5 of Colorado, have invented a certain new and useful Improvement in Calendars, of which the following is a full, clear, and exact description.

This invention is an improvement in calendar 10 ends of the so-called perpetual type, in which, by the adjustment of certain movable parts, a calendar is provided which will correctly show any month of a large predetermined number of years.

15 The objects of my invention are to provide a calendar which shall have a minimum number of parts and which shall be capable of being made of so small size and inconsiderable thickness as to be carried in the pocket 20 or to be made as a part of the ordinary pocket memorandum book without materially increasing the size of the book.

Other objects and advantages of my invention will later appear in the specification 25 and be pointed out in the appended claims.

To these ends my invention consists in the structure shown in the accompanying drawings in which,

Figure 1 is a plan or face view of my entire device; Fig. 2 shows, on reduced scale, how the calendar may be folded to accommodate it to insertion into the pocket or into a book; Fig. 3 is a diagrammatic view showing the various thicknesses of material employed in building up the calendar; Fig. 4 is a plan view, on a reduced scale, of the element in which the tab bearing the numerals corresponding to the days of the month is adapted to slide; Fig. 5 is a similar 40 view of the element in which the month and year indicating disks revolve; and Fig. 6 is a perspective, on the same scale as Figs. 4 and 5, of the tab which carries the numerals corresponding to the days of the month, 45 only two of these numerals, the ones which appear on a projection on the face of said tab, being shown.

The calendar consists essentially of a front or face member 7, which is twice the length 50 of the remaining members, a rear or backing member 8, a rectangularly slotted member 9 directly back of the face member, a partition 10, and a circularly recessed member 11 between the partition and rear member, together with the numeral carrying slide 12 and the month and year indicating disks 13

and 14. Inasmuch as the slide 12 and the disks 13 and 14 are embraced in the elements 9 and 11 they do not add to the thickness of the device and there are, when the face 7 is not folded up, but five thicknesses of material which, being made of paper, card-board, celluloid, thin metal or other suitable material, may be comprised within a very inconsiderable thickness. A very material reduction in bulk is thus attained over those devices which include one or more endless belts traveling on rollers or similar suspending means. It will, of course, be understood that two or more of these parts may be permanently secured together or may be formed in one piece, and in fact I prefer to make the parts 9, 10 and 11 as a unit, but for purposes of explanation it is simpler to speak of them as though they were all detached and joined only on their edges.

The face member 7 has a rectangular opening 15, and adjacent thereto, preferably above as shown, there is a table 16 of the days of the week. Openings 17 and 18 are also conveniently located in the face member 7 over the disks 13 and 14, and I prefer to place these as shown directly above the table of the days of the week—though any other proper location with reference to the disks 13 and 14 will answer. Also on the face member 7 and below the opening 15 is located a table showing the months in a vertical column and years in vertical and horizontal columns. The month column is just at one side of the vertical forming one side of the opening 15, and the vertical year columns, which are seven in number, are of the same width and directly under the spaces of the table 16 where are printed the days of the week.

The numeral carrying slide 12 is divided into thirteen spaces in a horizontal direction and six spaces vertically. The numeral 1 appears in the middle space of the upper row and the remaining spaces to the right are taken up by the numerals up to 7; the second row reads from 2 to 14; the third from 9 to 21; the fourth from 16 to 28; the fifth from 23 to 31; and the sixth from 30 to 31 as shown; the arrangement of the numerals and the size of the opening 15 being such that there is always exposed in the opening 15 numerals reading from 1 to 31. A projecting portion 19 is provided on the slide 12 by which the slide may be manipulated to place the numeral 1 over

any desired vertical column of years. In this instance the projection is shown as being constituted by a raised portion of the slide body and as being occupied by the numerals 5 15 and 22, but any other similar projecting means, such as a pin or the like, could be substituted therefor without departing from my invention. The operating means, however, should be located in the vertical column 10 under the numeral 1 as that is the only portion of the slide which is always exposed.

The operation of this part of my device is as follows: Given any desired month and 15 year, to display the proper arrangement for that month of numerals on the slide 12 with relation to the days of the week as appearing in the table above: Look in the horizontal column in the lower table opposite the month 20 in question until the desired year is found and then move the slide 12 until the numeral 1 is over the year selected; the calendar for the month in question will then be displayed in the opening 15, and the day of the week 25 on which any particular date occurred may be determined by reference to table 16 above the slide.

As previously stated month indicating disks 13 and year indicating disks 14 are 30 mounted in circular recesses 19 and 20 in the member 11 which is between the back 8 and the partition 10. Openings similar to 17 and 18 are provided in the partition 10 and these register with the said openings 17, 3 and 18 and these openings are of such size that the name of only one month on the disk 13 or the figures representing one year only on the disk 14 will appear in said openings. If it is desired to use the device as 40 an ordinary calendar the disks 13 and 14 may be turned to indicate the month and year for which the calendar is set, though these parts are used only as indicators and do not form a part of the mechanism of the 45 calendar proper, which latter it will be evident is capable of adjustment by a single operation—that of moving the slide 12.

The slide 12 always shows numerals from 1 to 31 but the proper number of days for 50 any month may be readily determined by reference to the column of months where this information is given. Asterisks, or other similar indicating means may be added to the year columns to show which are leap 55 years.

It will also be obvious that the table of years may be indefinitely enlarged at will to show any desired number of years, those chosen being merely given for purposes of illustration, or that the relative positions of the lower table and the table 16 may be reversed; and that these and various other changes of arrangement and so forth may be made without departing from my invention.

Having thus described my invention, what I claim and desire to secure by Letters Patent is:

1. In a calendar, a face member having a plurality of openings therein, one of said openings being larger than the others, a week table on said face member, a slide having the days of the month thereon divided into thirteen vertical columns, any seven of which columns comprises a complete mensual calendar, said slide being adapted to move back of said face member, through the larger opening of which seven of its columns are always exposed, an element embracing said slide and in which it travels, a circularly recessed member, month and year indicating disks revolvably mounted in the recesses of said last mentioned element in operative relation to the remaining openings in said face member, and a backing element:

2. In a calendar, a face member having a plurality of openings therein, one of said openings being larger than the others, a week table on said face member, a slide having the days of the month thereon divided into thirteen vertical columns, any seven of which columns comprises a complete mensual calendar, said slide being adapted to move back of said face member, through the larger opening of which seven of its columns are always exposed, an element embracing said slide and in which it travels, a partition having slots therein which register with the remaining openings in the face plate, a circularly recessed member back of said partition, month and year indicating disks revolvably mounted in the recesses of said last mentioned element in operative relation to the slots, and a backing element.

In testimony whereof, I hereunto affix my signature in the presence of two witnesses.

SAMUEL K. JENSIK.
